UNITED STATES PATENT OFFICE.

NELSON GOODYEAR, OF NEW YORK, N. Y., ASSIGNOR TO J. B. COLT COMPANY, OF NEW YORK, N. Y., A CORPORATION OF NEW JERSEY.

GAS-GENERATOR.

967,183.

Specification of Letters Patent. Patented Aug. 16, 1910.

Application filed August 2, 1906. Serial No. 328,874.

To all whom it may concern:

Be it known that I, NELSON GOODYEAR, a citizen of the United States, and resident of the borough of Manhattan, city, county, and State of New York, have invented certain new and useful Improvements in Gas-Generators, of which the following is a specification, accompanied by drawings.

This invention relates to gas generators, more especially to apparatus for generating acetylene gas, and the objects of the invention are to improve upon the construction of such generators, render them certain and efficient in operation and provide for the safety of the apparatus at all times and under all circumstances, thereby preventing accidents in use.

Another object of the invention is to enable the generator to be flushed out and charged with water and carbid without admitting air to said tank, and to make the admission of air to the tank or an escape of gas from the tank impossible.

Further objects of the invention will hereinafter appear, and to these ends the invention consists of a generator for carrying out the above objects embodying the features of construction, combinations of elements and arrangement of parts having the general mode of operation substantially as herein-after fully described and claimed in this specification, and shown in the accompanying drawings, in which,—

Figure 1 is a side elevation partly in section of apparatus embodying the invention; Fig. 2 is a longitudinal sectional elevation of the same; Fig. 3 is a plan view; Fig. 4 is an enlarged detail elevation partly in section on the line *e*—*f* of Fig. 5; Fig. 5 is a detail plan view partly in section on the line *a*—*b* of Fig. 4; Fig. 6 is a horizontal sectional detail view on the line *c*—*d* of Fig. 4; Fig. 7 is an enlarged detail elevation partly in longitudinal section taken through the carbid feeding mechanism; Fig. 8 is an enlarged detail transverse sectional plan view on the line *g*—*h* of Fig. 7; Fig. 9 is a detail perspective view, partly broken away, of a portion of the interlocking connections.

The generator tank *A* is provided with a suitable carbid hopper *B* supported upon the neck *C*, and in the hopper is arranged suitable carbid feeding mechanism, in this instance shown as a valve *D* moving in a protective casing *E*, while between the casing

and the valve is a stop *F*, which is raised by the valve *D* after the valve is raised, and which seats itself before the valve is seated. Any other suitable form of valve may be provided if desired. 60

The valve *D* is adapted to be controlled by the gas pressure in the gasometer *G*, which, as shown, is provided with a rising and falling gas bell *H*, and suitable operative connections are provided between the gas bell and the valve for operating said valve. In this instance an arm *a* is connected to be operated by the rock shaft *b*. When the shaft *b* is rocked in one direction the valve *D* will be raised, and when the shaft is released the valve will fall by its own weight. The arm *a* is suitably connected to the rock shaft *b*, in this instance a squared portion being provided upon the rock shaft which is thrust through the end 75 of the lever. The rock shaft *b* extends through a stuffing box *c* and is provided with an arm *d* loose thereon, having a bearing *e* in which is supported a small rock shaft *f*. Suitably secured to the rock shaft *f* is a latch *g* adapted to coöperate with a hook *h* secured fast to the rock shaft *b* in any suitable manner by means of the hub *i*. A spring *j* secured to the latch *g* and also to a projection *k* on the arm *d* holds the latch 85 normally in engagement with the hook so that downward movement of the arm *d* will rock the shaft *b*. The other end of the rock shaft *f* is provided with a finger *l* secured fast thereon and projecting over a stop *m* 90 projecting from the casing, so that at the downward limit of the movement of the arm *d* the finger *l* will engage the stop *m* and rock the shaft *b*, thereby releasing the latch *g* from the hook *h*, and permitting the rock shaft *b* to rotate and close the valve *D* in the hopper. The arm *d*, as shown, is suitably connected to a rod *o* pivoted to a link *p*, which is in turn pivoted to a bracket *q* on the gasometer bell *H* so that downward movement of said bell will rock the shaft *b* and open the valve *D*, while upward movement of the gasometer bell *H* will permit the valve *D* to close. Any other suitable operative connections may be provided for 100 carrying out these objects. 105

The hub *i* of the hook *h* is provided with an arm *l* extending substantially parallel to the arm *d*. By depressing the arm *l*, the hook *h* may be brought into engagement 110.

with the latch *g*. In starting the apparatus, by slightly depressing the outer end of the arm 17 some carbid is then fed into the water and the generation of gas causes the 5 gasometer bell to rise, thereby rocking the rock shaft *b* and bringing the latch *g* into engagement with the hook *h* automatically to enable the apparatus to operate thereafter.

The carbid hopper *B* is provided with a 10 cover *I*, and the tank *A* is provided with a flush out cock *J* and a water charging device in the form of a water inlet valve *K* in the water pipe *L*. The gas educting pipe *O* passes from the tank *A* into the gasometer 15 *G*, and is provided with a downwardly extending gas pipe *Q*, which passes through the partition *R* in the gasometer.

S represents the service pipe connecting with the drain pipe *T* and the gas outlet 20 pipe *U* which has a telescoping cap *V* provided with gas apertures *W*. The telescoping portion *V*, as shown, is connected by means of the rods or chains *X* to the gasometer bell *H* and thus rises and falls with 25 said bell. The gasometer bell *H* is guided on the central shaft *Y* by means of the guiding sleeve *Z*, and suitable means are provided for preventing the bell from rotating about the axis of the shaft *Y*, in this instance a tubular upright *r* being provided 30 extending from the partition *R* while a sleeve *s* connected to the gasometer bell *H* telescopes over the upright *r* and is guided by the bracket *t*, thus preventing the bell 35 from turning and deranging the carbid feeding mechanism and also forming a telescopic blow off.

u represents an overflow pipe on the gas generating tank *A*, and as shown the flush 40 out *J* is somewhat above the level of the opening of the flush out pipe leading into the tank *A* so that the said opening is always water sealed.

In the gas educting pipe *O* is arranged a 45 gas valve *v* of any suitable character, and in connection with the valve chamber a pipe *w* is provided leading to the atmosphere. The valve *v* is in this instance provided with a central opening 2 and an auxiliary opening 3, thus making the valve substantially 50 a three-way valve. When the machine is empty of both carbid and water and it is desired to start it for the first time in operation generating gas, let it be assumed that 55 the first operation is to charge in the water in the tank *A*.

Means are provided for insuring that the 60 gas valve *v* shall be open to permit communication between the generator tank *A* and the gasometer when water is being charged in to the generator tank, so that the gas in the generator tank may pass into the gasometer and out through the service pipe *S* or cock *S'*. In order to accomplish this

end the valve *v* is provided with a horizontally arranged segmental plate 4 connected to the valve spindle in any suitable manner, as by means of the screw 5. This plate is provided with an aperture 6 adapted to register with a rod 7 connected to the handle 70 8 of the water valve *K* when the gas valve *v* is open, thereby permitting the handle 8 and rod 7 to be raised to open the water valve *K* and let water into the generating chamber *A*. The segment 4 is preferably provided 75 with a handle 9 in order that it may be turned, and in all other positions of this segment the water valve *K* is prevented from being opened because the rod 7 cannot move upward, owing to the solid surface of 80 the plate above it.

After the water has been charged into the generating chamber *A*, let it then be desired to fill the carbid hopper *B* with carbid. In order to do this the carbid cover *I* must be 85 opened, and before the cover can be opened the carbid feeding mechanism connected to the valve *D* must be thrown out of operative relation or disconnected so that carbid cannot be fed, and the gas valve *v* must be 90 closed to close the gas pipe *O*, and at the same time open communication between the generator tank *A* and the small pipe *w* to permit any remnants of air to pass out to the atmosphere before the cover *I* is opened. 95 Before the segment 4 can be turned to close the gas valve *v* the stop 12 must be raised out of engagement with said plate or segment. As shown, the stop 12 is guided by a bracket 13 and is connected to a rod 14 100 having a handle 15, said rod being connected to a bell crank 16 pivoted on the carbid hopper. The other arm of the bell crank being provided with a link 18 having a slotted end 19 inclosing a stud 20 projecting from a 105 cam 21 loose on the end of the rock shaft *b* and adapted to bear against an arm 22 connected to the latch *g*, so that when the handle 15 is raised the stop 12 is moved out of engagement with the plate or segment 4, 110 and the bell crank lever 16 is rocked to raise the link 18 and thereby rotate the cam 21 on the rock shaft *b* and force the arm 22 upward, thus forcing the latch *g* out of engagement with the hook *h* to disconnect the 115 valve mechanism and permit the valve *D* to close of its own weight.

Before the cover *I* can be opened the segment 4 must be rotated to close the valve *v* and bring the enlarged portion 10 of the 120 curved slot 11 over the enlarged end 23 of the stop 24, thereby enabling said stop to be raised into engagement with the plate 4 and permit the cover *I* to be opened. The stop 24 is connected to a rod 25, in turn connected 125 to a bell crank 26, which is connected by a rod 27 to an arm 28, carried by the bail 29 pivoted at 30 to the hopper *B*. The cover

1 is provided with a cam-shaped portion 31, over which the bail 29 rides, so that when the bail is moved down over the cam 31 the arm 28 is raised, thereby rocking the bell 5 crank 26 and raising the rod 25, and also raising the stop 24 having the enlarged end 23 into engagement with the plate 4 thereby locking the plate. The carbid hopper B may now be filled with carbid without danger of accidents because the carbid feeding mechanism is disconnected and the carbid valve D is closed. Communication between the generator tank A and the gasometer G is also cut off by the closure of the valve v. 10 Communication is, however, opened between the generator tank A and the pipe w leading to atmospheric air because the valve v has been turned to open said communication between the auxiliary opening 3 and the large opening 2 in said valve, to permit the escape of any remnants of air that may be contained in the generating chamber. Another condition must also have been fulfilled before the segment 4 could be turned to close 15 the valve v and release the carbid cover I, namely, the closure of the flush out J, for the valve v cannot be closed as long as the flush out is open. Furthermore the flush out must be closed before the carbid cover I can be opened, and the opening of the carbid cover and the closure of the gas valve v both prevent the opening of the flush out until the carbid cover is again closed and the gas valve v opened. As shown, the lower end of the spindle of the valve v is provided with a crank arm 32 which turns with the valve, and to the end of this crank is connected a rod 33 connected to an arm 34 pivoted on the generator tank, which arm is in turn connected by a rod 35 to a bell crank 36, the other arm of which bell crank is provided with a vertically movable stop 37 guided in the bracket 38 and adapted to register with an opening 39 in a horizontally 20 slidable plate 40. This plate 40 is also provided with an opening 41 adapted to register with the end of a rod 42 also guided in the bracket 38 and connected to a bell crank 43, which in turn is connected by a rod 44 with an arm 45 carried by the movable bail 29 of the carbid cover I. The slide 40, as shown, is provided with a pin 46 engaging a loop 47 forming one arm of a bell crank 48, the other arm of which is connected by a rod 55 25 to the flush out J. The closure of the flush out J moves the slide 40 into position to bring the apertures 39 and 41 under the stop 37 and the rod 42 respectively, so that when the segment 4 is turned to close the gas valve v the movement of the crank 32, which is transmitted to the bell crank 36 will force the stop 37 into the aperture 39, and the downward movement of the bail 29 to release the carbid cover I will force the rod 30

42 down into the aperture 41 in the plate 40, 65 thus providing a double lock to maintain the flush out closed as long as the carbid cover is open and the gas valve closed.

After the generator tank A has been filled with water and the carbid hopper B 70 has been charged with carbid and the cover I closed and the gas valve v opened, the apparatus is in condition to generate gas automatically, and gas will be generated until the supply of carbid in the hopper B is exhausted. A suitable auxiliary valve or stop 50 is pivoted to swing beneath the opening of the hopper B, and is connected to be controlled by the level of the water in the tank A. As shown, a suitable float 51 is provided connected by a link 52 to the side of the tank and guided by a projection 53 moving in the guide 54. The float 51 is suitably connected by a rod 55 to the pivoted stop 50, so that the float rises with the level 80 of the water and opens the stop 50. The sinking of the water level swings the stop 50 under the opening of the carbid hopper B and prevents feeding of carbid. 85

The operations on starting the machine 90 for the first time when it is empty of both carbid and water have been described, let it now be assumed that the machine has been in operation for some time generating gas, and that the supply of carbid in the hopper 95 is exhausted leaving the tank substantially full of water and residuum, the carbid hopper may first be charged with carbid to renew the operation of the apparatus or else the generator tank A may first be 100 flushed out to get rid of the residuum. In order to flush out the tank A it has been shown that the carbid cover I must be closed to raise the rod 42 out of engagement with the plate 40, and the gas valve v must be 105 turned to open position, as shown in Figs. 5 and 6, to raise the stop 37 out of engagement with the plate 40.

Means are provided for throwing the carbid feeding mechanism out of operative relation when the flush out J is opened, so that carbid cannot be fed. As shown, the looped end 47 of the bell crank 48 to which the flush out is connected, is also connected by a rod 56 with the carbid feeding mechanism. Said rod 56 has a loop 57 at its end which passes over the pin 20 on the cam 21 so that when the flush out J is raised to open it the bell crank lever 48 is rocked and the rod 56 is pushed forward, thus rotating the cam 21 on the end of the rock shaft b and moving the latch g out of engagement with the hook h to disconnect the carbid feeding mechanism and permit the valve D to close. The rods 18 and 56 are provided 115 with loops 19 and 57 at their ends and closing the pin 20 so that one rod may be moved to rotate the cam 21 without moving the 120 125

other rod. Thus the rod 18 may be raised to disconnect the carbid feeding mechanism and the pin 20 will simply move in the loop in the end of the rod 56. When the rod 56 is moved upward the cam 21 is rotated and the pin 20 moves up in the loop in rod 18.

No vent to atmospheric air is provided when the generator tank A is being flushed out and instead gas from the gasometer bell 10 H is permitted to pass over through the gas pipe O and valve v to take the place of the water as it recedes in the tank A. The design and arrangement of the apparatus is such that after all the carbid has been used 15 up in the hopper B and the gasometer bell H has sunk in the gasometer tank G, sufficient gas will be trapped in the bell H above the water to substantially fill the generator tank A when the water and residuum have 20 been flushed out. In order to accomplish this end provision is afforded for the automatic closure of the gas pipe U in the gasometer when the bell has sunk to a predetermined distance. The telescoping tube V, 25 as shown, is always water sealed and the gas openings W are so situated that when these openings are closed by the water there will be sufficient volumetric space in the gasometer bell above the water to supply 30 enough gas to fill the generator tank A as the water is flushed out of said tank. As the water recedes in the tank A, gas passes over from the bell H and the bell sinks farther down, which is permitted by the rods 35 or chains X which simply pass down loosely through openings in the rod or plate 60. These chains or rods X are provided with stops or balls 61 which engage the plate 60 and raise the telescoping cap V when gas is 40 again generated in the generator. On again charging water into the generator tank A after it has been flushed out, the gas valve v must be open and the gas in the generator tank passes back through the pipe O into 45 the gasometer and out of the cock S'.

This invention has for one of its principal objects to prevent the entrance of air into the generator tank both on charging in water or upon flushing out. As the water 50 and residuum are drawn off from the tank sufficient gas which has been trapped in the gasometer is permitted to flow over from the gasometer into the tank to displace the liquid. Upon charging in water, the gas 55 flows back into the gasometer and from thence passes off through the service pipe or to atmospheric air. Therefore the venting of the gas space of the generator is prevented both on charging in water and upon 60 flushing out.

Obviously some features of this invention may be used without others and the invention may be embodied in widely varying forms, therefore, without limiting the invention to the devices shown and described,

and without enumerating equivalents, I claim and desire to obtain by Letters Patent the following:

1. In a gas generator, the combination with the generator tank and gasometer, of means for trapping an amount of gas in the gasometer sufficient to fill the volumetric space of the generator tank when said tank is substantially flushed out, and a gas connection between the generator tank and gasometer. 75

2. In a gas generator, the combination with the generator tank and gasometer, of means for trapping gas in the gasometer, a gas connection between the generator tank 80 and gasometer, a valve in said connection and means for insuring that said valve shall be open when the generator tank is flushed out and when water is charged into said tank. 85

3. In a gas generator, the combination with the generator tank and gasometer, of means for trapping gas in the gasometer, a gas connection between the generator tank and gasometer, a valve in said gas connection, 90 and means for insuring that said valve shall be open when the generator tank is flushed out.

4. In a gas generator, the combination with a generator tank and gasometer, of means for trapping gas in the gasometer, a gas connection between the tank and gasometer, a valve in said connection and means for insuring that said valve shall be open when water is charged into the generator 100 tank. 105

5. In a gas generator, the combination with the generator tank and gasometer, of means for trapping gas in the gasometer, a gas connection between the said tank and 110 gasometer, a valve in said connection, means for preventing the generator tank from being flushed out without opening the valve in said gas connection.

6. In a gas generator, the combination with the generator tank and gasometer, of means for trapping gas in the gasometer, a gas connection between the said tank and gasometer, a valve in said connection, and means for preventing water from being 115 charged into said tank without opening the valve in said gas connection. 120

7. In a gas generator, the combination with the generator tank and carbid hopper of a flushing out device, a gas educting pipe, a gas valve, and means for preventing the carbid cover from being opened when the gas valve and flush out are open.

8. In a gas generator, the combination with the carbid hopper and cover, of a gas 125 educting pipe, a water charging device and means for preventing the cover from being opened when said pipe and the water charging device are open.

9. In a gas generator, the combination 130

with the carbid hopper, cover and feeding mechanism, a gas educting pipe, a valve therein, and means for preventing the carbid cover from being opened until the feeding mechanism is disconnected and the gas valve open.

10. In a gas generator, the combination with the carbid hopper, cover, feeding mechanism and gas educting pipe, of a valve in said pipe and means for preventing the closure of said valve until the carbid feeding mechanism is disconnected.

11. In a gas generator, the combination with the carbid hopper, cover, feeding mechanism and gas educting pipe, of a valve in said pipe, and means for disconnecting the feeding mechanism when said valve is closed.

12. In a gas generator, the combination with the carbid hopper, cover, feeding mechanism, gas pipe, and a valve in said pipe, of means for disconnecting the feeding mechanism when said cover is open and said valve closed.

13. In a gas generator, the combination with a water charging device, a gas pipe and means for preventing water from being charged into the generator unless the gas pipe is open.

14. In a gas generator, the combination with the carbid hopper and cover, of a flushing out device, a gas pipe and means for preventing the generator from being flushed out until the gas pipe is open and the cover closed.

15. In a gas generator, the combination

with the generating chamber, of a gasometer, a gas educting pipe, a hopper, a carbid cover, a water charging device and means for preventing the opening of the water charging device unless the carbid cover is closed and the gas pipe open.

16. In an apparatus of the character described, the combination of a generator chamber adapted to contain water, a gasometer mounted apart of said generator chamber and connected therewith, means for discharging said generator, means for measuring a predetermined amount of gas in the bell and means causing said measured amount of gas to be conducted to the generator to replace the water discharged.

17. In an apparatus of the character described, the combination of a generator chamber adapted to contain water, a gasometer mounted apart of said generator chamber and connected therewith, means for discharging said generator, means for measuring a predetermined amount of gas in the bell and means causing said measured amount of gas to be conducted to the generator to replace the water discharged and returned again to the gas-bell when the generator is recharged with water.

In testimony whereof I have signed this specification in the presence of two subscribing witnesses.

NELSON GOODYEAR.
